David E. Crooker, Ontonagon, Mich., and Evan A. Frary,
Marshfield, Wis.; said Frary assignor to Lloyd L. Felker,
Marshfield, Wis.

Application November 9, 1953, Serial No. 27,513

Term of patent 14 years

(Cl. D90—20)

Fig. 1.

Fig. 2.

Figure 1 is a frontal perspective view of an automobile tire showing our new design; it being understood that the full line portion is repeated throughout the tread circumference of the tire illustrated in dotted lines; and

Fig. 2 is an enlarged fragmentary sectional view of a single tread element.

The predominant and characteristic feature of our design resides in the design of the tread as shown in full lines in Fig. 1.

We claim:

The ornamental design for an automobile tire, substantially as shown and described.
